Atty.

UNITED STATES PATENT OFFICE.

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

PRESSURE-FLUID-OPERATED TOOL.

Application filed February 1, 1926. Serial No. 85,115.

More particularly the invention relates to a pressure fluid operated tool embodying a reciprocating piston and a slideable sleeve valve, such as, for example, a pneumatic riveting hammer, it being the general object of the invention to provide new and useful improvements in a tool of this type whereby the efficiency and effectiveness of the tool are increased.

10 A further object of the invention is to provide in a tool of this type, improved means whereby the pressure fluid may act to shift the valve quickly and to effectively retain the valve in its shifted position.

15 In pursuance of the foregoing objects, I aim to provide in a pressure fluid operated tool embodying a reciprocating piston, a sliding valve adapted to control the inlet and exhaust of pressure fluid to reciprocate 20 said piston, a chamber adjacent a flange on said valve, a passage thereto controlled by the piston, and means including an inlet passage adapted to admit pressure fluid to vacuumize said chamber, to retain the valve 25 in one position, the pressure fluid admitted through said inlet passage acting against said flange to shift said valve when the piston-controlled passage is closed.

Further objects and advantages of the 30 invention will be understood from the following detailed description taken in connection with the accompanying drawings, in which:

Figure 1 is a view partly in central longitudinal section of a tool embodying one 35 form of the invention, wherein the valve is shown in its forward position.

Fig. 2 is a fragmental central longitudinal section in a plane at an angle to that of Fig. 1, wherein the valve is shown in its 40 rear position. The view is somewhat diagrammatic in that the passage to the forward end of the piston chamber is shown in a plane different from that of Fig. 1 for the sake of clearness.

For purposes of disclosure, I have illustrated in the drawings and will hereinafter describe in detail the preferred embodiment 45 of the invention with the understanding that I do not intend to limit the invention to the particular construction and arrangement shown, it being contemplated that various changes may be made by those skilled in the

art without departing from the spirit and scope of the appended claims.

55 Referring to the drawings, the invention in the exemplary form is shown as embodied in a riveting hammer comprising a barrel 1 forming a piston chamber 2, a piston 3 mounted for reciprocation therein, a tool 4 suitably mounted in the barrel at the forward end of the piston chamber and retained therein by a customary clip 5, and a handle 6 secured to the rear end of the barrel by means of the screw threads 7.

65 Adjacent the handle end the barrel 1 is preferably counterbored to admit a cylindrical valve casing 8, said casing being secured in the barrel between the shoulder formed at the bottom of the counterbore, and the handle 6. Within this casing 8 a tubular valve 9 having an internal bore corresponding to that of the piston chamber 2, is 70 slidably mounted.

A supply passage 10 in the handle 6 leads 75 to an annular supply chamber 11 formed between the rear end of the barrel 1, the valve casing 8 and the handle. From this supply chamber a plurality of passages 12 lead to an annular recess 13 in the piston chamber 20 to provide an inlet passage to the rear end thereof. In addition to this inlet passage to the rear end of the piston chamber, an inlet passage is provided to the forward end of the piston chamber, which passages together 80 with exhaust passages from the forward and rear end of the piston chamber are adapted 90 to be controlled by the slide valve 9.

95 In the preferred form the valve 9 is provided with annular flanges 14 and 15 and an annular groove 16, the flanges respectively engaging annular grooves 17 and 18 in the valve casing 8. In addition to these grooves the said valve casing is provided with annular ports 19 and 20 and an annular recess 21, the port 20 being in constant communication with the atmosphere through an exhaust port 22 in the valve casing 8 and barrel 1, and the port 19, being in communication with the forward end of the piston chamber 2 through a passage 23 formed also in the said valve casing and barrel. The valve casing 8 is further provided with an exhaust passage 25 leading from the rear portion of the groove 18 to the exhaust port 110 22, and an inlet passage 26 leading from one

of the passages 12 to a port 26^a in the casing which communicates with the groove 16 in the valve 9 when the valve is in its rear position. The inlet passage 26 is also connected with the groove 18 by a port 26^b leading to the forward portion of said groove. This port is closed by the valve in its forward position as shown in Fig. 1 but is uncovered by the valve in the initial portion of its rearward movement. A valve control passage 27 in the valve casing and barrel establishes communication between the forward portion of the groove 18 and a port 28 in and intermediate the ends of the piston chamber 2. A port 24 connects the recess 21 with said passage 27.

Adjacent the rear end of the piston chamber 2 connecting passages 29 and 30 are provided in the valve casing 8, the passage 29 leading to a rear valve chamber 31 formed between the valve flange 14 and the casing groove 17, and the passage 30 communicating with the piston chamber 2 to the rear of the valve 9. An inlet port 32 in the valve casing 8 establishes constant communication between the supply chamber 11 and the passage 30 and, preferably, is adapted to direct motive fluid into the passage 30 in a manner such as to exhaust into the piston chamber 30 and to vacuumize the passage 29 and chamber 31 and thereby create a suction on the flange 14.

The operation of the tool embodying the exemplary form of the invention is as follows: Assuming the valve 9 to be in its forward position as shown in Fig. 1, motive fluid in the supply passage 10 is admitted to the rear end of the piston chamber 2 through an inlet passage comprising the annular supply chamber 11, passages 12 and the recess 13 in the valve casing. The piston 3 is driven forward by the pressure fluid thus admitted, the portion of the piston chamber forward of the piston exhausting through an exhaust passage comprising the longitudinal passage 23, annular groove 19 in the casing 8, groove 16 in the valve 9, groove 20 in the casing and exhaust port 22. During the forward stroke of the piston the valve 9 is held in its forward position by the force exerted against the rear surface of the flange 14 by the motive fluid entering chamber 31 from the piston chamber through the connecting passages 29 and 30. The forward end 9^a of the valve is vented to exhaust through recess 21, and ports 24, 27 and 28 to the piston chamber forward of the piston so that leakage from the piston chamber to the forward end of the valve will not act to move the valve rearwardly.

As the piston moves forward it uncovers the port 28 in the piston chamber thereby admitting pressure fluid through the longitudinal control passage 27 to the groove 18 and through port 24 to recess 21, to exert a

force against the flange 15 and against the forward end 9^a of the valve 9, to thereby move the valve to its rear position, the force exerted on the flange 15 and said forward end 9^a of the valve being greater than that on the rear surface of the flange 14 because of the greater area of the flange 15 and the valve end 9^a. Immediately upon the initial movement of the valve rearwardly, line pressure fluid is admitted from passage 26 through the port 26^b to the groove 18 to act against the forward surface of the flange 15 to assist in the completion of the rearward movement of the valve and in holding the valve in its rear position.

The movement of the valve 9 to its rear position cuts off the pressure fluid supply to the rear end of the piston chamber by closing the recess 13 and permits exhaustion thereof through the annular port 20 and exhaust port 22. The valve 9 is then held in its rear position by the line pressure fluid admitted to the flange 15 through port 26^b, and also by a suction on the flange 14 caused by the partial vacuum created in the chamber 31 and passage 29 by the jet of motive fluid entering through the inlet passage 32, if said passage is directed to discharge the fluid across the end of passage 29 into the passage 30 and piston chamber 2.

The port 28 in the piston chamber is so positioned as to correctly time the movement of the valve to its rear position with the impact of the piston on the tool 4 in order that immediately upon the impact, pressure fluid is admitted to the forward end of the piston chamber to return the piston.

As shown in Fig. 2, the valve 9 in its rear position has opened an inlet passage to the forward end of the piston chamber in addition to opening the exhaust passage from the rear portion of the piston chamber as hereinbefore described. The inlet passage thus opened comprises the passage 12 in communication with the supply chamber 11, the passage 26 in the valve casing 8, groove 16 in the valve, port 19, and the longitudinal passage 23 in the valve casing and barrel. The flow of pressure fluid in passage 26 past the port 26^b relieves the pressure to some extent in said port and also in groove 18.

The pressure fluid thus admitted is adapted to return the piston, the piston in its return stroke uncovering the port 28 which permits a portion of the motive fluid in the piston chamber forward of the piston to exhaust into the piston chamber to the rear of the piston through the passages 27 and 24. When upon further movement on the return stroke the piston covers the end of the passage 30, the pressure fluid entering through the port 32 creates a pressure in the chamber 31 which acts upon the rear surface of the flange 14 and moves the valve quickly to its forward position, whereupon pressure

fluid is again admitted through the passages 12 and port 13 to the rear of the piston chamber to drive the piston forward.

It will be apparent that by positioning 5 the port 30 to lead into the piston chamber to the rear of the valve a short piston may be used if desired. If the port connected with the piston chamber forward of the valve a short piston might uncover the port 10 when the piston is in its extreme rearward position and thereby make the tool inoperative.

The constantly open inlet passage 32, in conjunction with passages 29 and 30, admits 15 pressure fluid at practically line pressure to move the valve quickly and positively to its forward position, and thereby insures a prompt operation of the valve to admit pressure fluid to drive the piston forward. As 20 during the forward stroke of the piston, pressure fluid is admitted to the chamber 31 from the piston chamber through passages 30 and 29, there is practically no movement of air through the restricted inlet 32 but 25 when the rear portion of the piston chamber is exhausting on the return stroke of the piston, the inlet passage 32 when positioned as illustrated in the preferred form, discharges pressure fluid through passage 30 30 and effectively retains the valve in its rearward position.

I claim as my invention:

1. A pressure fluid operated tool having, 35 in combination, a barrel forming a piston chamber, a piston mounted for reciprocation in said piston chamber, a tool adapted to be impacted by said piston, a tubular valve slidable within said barrel, said valve having an internal bore corresponding with that of the 40 piston chamber and being movable to control the inlet and exhaust of pressure fluid to reciprocate said piston, an annular flange on said valve, means to admit pressure fluid intermittently against said flange to move 45 said valve to its rear position, a second annular flange surrounding said valve and slidably engaging a groove in said barrel to form a rear valve chamber, an exhaust passage connecting said rear valve chamber 50 with the said piston chamber at a point to the rear of said valve, and a constantly open inlet port leading to said exhaust passage and adapted to direct pressure fluid through said exhaust passage in a direction to 55 vacuumize said rear valve chamber, said piston, in its reciprocation, closing said exhaust passage whereupon the motive fluid constantly admitted by said inlet port intermittently creates a pressure in said rear valve 60 chamber to shift the valve forward.

2. A pressure fluid operated tool having, 65 in combination, a barrel forming a piston chamber, a piston reciprocable in said chamber, a tubular valve slidable in said barrel and adapted to control the admission and

exhaust of pressure fluid to the said piston chamber to reciprocate said piston, said valve having an external annular flange engaging a groove in said barrel to form a rear valve chamber, and means to operate said valve 70 including an exhaust passage connecting said rear valve chamber with the portion of the piston chamber to the rear of said valve, and an inlet port leading to said exhaust passage and adapted to direct pressure fluid 75 through said exhaust passage in a direction to vacuumize said rear valve chamber.

3. A pressure fluid operated tool having, in combination, a barrel forming a piston chamber, a piston reciprocable in said chamber, a tubular valve slidable in said barrel and adapted to control the admission and exhaust of pressure fluid to the said piston chamber to reciprocate said piston, means to reciprocate said valve, and means to 80 retain said valve at one end of its travel including an external flange on said valve and means to utilize pressure fluid to create a suction on said flange including a constantly open inlet port opening into said piston 85 chamber to the rear of said valve.

4. A pressure fluid operated tool having, in combination, a barrel forming a piston chamber, a piston reciprocable in said piston chamber, a tubular valve slidable within 90 said barrel and having an internal bore corresponding with that of the piston chamber, an external flange on said valve slidably engaging a groove in said barrel to form a rear valve chamber, a passage connecting said 95 rear valve chamber with the portion of said piston chamber to the rear of said valve, and an inlet port leading to said passage adapted constantly to discharge pressure fluid through said passage into the piston 100 chamber, said piston in its reciprocation periodically closing said passage thereby causing the pressure fluid constantly admitted to intermittently exert a pressure in said 105 valve chamber and against said flange to move said valve forward.

5. A pressure fluid operated tool having, in combination, a barrel forming a piston chamber, a piston reciprocable in said chamber, a valve slidable in said barrel and 110 adapted to control the admission and exhaust of pressure fluid to the said piston chamber to reciprocate said piston, and means to reciprocate said valve including an external annular flange on said valve 115 engaging a groove in said barrel to form a valve chamber, an exhaust passage for said valve chamber and a constantly open inlet passage leading to said piston chamber at the rear of said valve adapted to admit 120 pressure fluid to exhaust said valve chamber through said exhaust passage and to hold the valve in one position, said passage being periodically closed at its discharge end by the said piston in its reciprocation to 125 130

cause the pressure fluid admitted by said inlet passage to move the valve forward.

6. A pressure fluid operated tool having, in combination, a barrel forming a piston chamber, a piston reciprocable in said chamber, a valve slidable in said barrel and adapted to control the admission and exhaust of pressure fluid to the said piston chamber to reciprocate said piston, and means to reciprocate said valve including a rear flange surface on said valve adapted to be acted upon by pressure fluid to move the valve forwardly during the return stroke of the piston, a constantly open inlet port admitting pressure fluid to said surface, and an exhaust passage leading to the portion of said piston chamber to the rear of said valve and normally open to relieve said pressure on said surface, said exhaust passage being closed by the piston in its reciprocation.

7. A pressure fluid operated tool having, in combination, a barrel forming a piston chamber, a reciprocatory piston, a reciprocatory valve, inlet and exhaust passages to said piston chamber controlled by the opposite ends of said valve, a valve control passage opening into the mid-portion of said piston chamber adapted to be uncovered by the rearward end of the piston as it travels forwardly, means controlled by the valve in the initial portion of its rearward movement to admit pressure fluid to assist in completing the rearward movement of the valve, means controlled by the valve operating when the valve is in its rearmost position to supply pressure fluid to the forward piston chamber to move the piston rearwardly, and a port communicating at all times with

said control passage and with said exhaust passage when the valve member is in its 40 rearmost position.

8. A pressure fluid operated tool having, in combination, a barrel forming a piston chamber, a reciprocatory piston, a reciprocatory valve adapted to control the inlet and exhaust of pressure fluid to reciprocate said piston, means to reciprocate said valve including a valve control passage governed by said piston and a port uncovered in the initial movement of said valve in one direction to admit pressure fluid to assist in completing the movement of the valve, and means to create a suction to hold the valve in one of its positions including a constantly open inlet port opening into said piston chamber to the rear of said valve.

9. A pressure fluid operated tool having, in combination, a barrel forming a piston chamber, a reciprocatory piston, a reciprocatory valve, inlet and exhaust passages to said piston chamber controlled by the opposite ends of said valve, a valve control passage opening into the mid-portion of said piston chamber adapted to be uncovered by the rearward end of the piston as it travels forwardly, means controlled by the valve operating when the valve is in its rearmost position to supply pressure to the forward piston chamber to move the piston rearwardly, and a port communicating at all 70 times with said control passage and directly with said piston chamber adjacent the forward edge of the valve.

In testimony whereof, I have hereunto affixed my signature.

ERNEST H. SHAFF.
